UNITED STATES PATENT OFFICE.

WILBERT W. LAMB, OF CHICAGO, ILLINOIS.

DEVICE FOR BURNING VEGETATION AND MELTING SNOW AND ICE.

No. 851,011.

Specification of Letters Patent.

Patented April 23, 1907.

Application filed December 15, 1905. Serial No. 291,942.

To all whom it may concern:

Be it known that I, WILBERT W. LAMB, a citizen of the United States, residing at Chicago, in the county of Cook and State of Illinois, have invented certain new and useful Improvements in Devices for Burning Vegetation and Melting Snow and Ice, of which the following is a specification.

My invention relates to improvements in devices for burning vegetation and melting snow and ice on railways and highways; and the objects of my improvement are, first, to provide a generator of such form and capacity as to supply hydrocarbon fuel in a gaseous state in a sufficient quantity to burn vegetation or melt snow and ice, moving the vehicle more rapidly than has been possible heretofore.

With the above and other objects in view this invention consists of the novel forms and the combinations and arrangement of parts hereinafter more specifically described, illustrated in the drawings, and particularly pointed out in the claims.

In describing the invention in detail reference is had to the accompanying drawings, forming a part of this specification, wherein like numerals of reference indicate corresponding parts throughout the several views, and in which—

Figure 1 is a side elevation of the vehicle for surface work. Fig. 2 is a side elevation of the car for railroad-work. Fig. 3 is a bottom plan view of the burner mechanism. Fig. 4 is a vertical section of a Bunsen burner, and Fig. 5 is a section on line 5 5 of Fig. 3.

Any suitable vehicle may be used. I have shown an automobile of the power-driv type, adapted to run upon a railroad-track and upon the highways and the streets.

The different parts of my invention are mounted upon and made operative in connection with a self-propelling vehicle or car, (shown in Figs. 1 and 2,) which vehicle, in addition to the necessary and usual motor and mechanism for self-propulsion, carries an ordinary air-pump operatively associated with the driving power of the vehicle for the purpose of supplying air-pressure in the fuel-tank.

It is thought not necessary to show or describe the motive power of the vehicle or the air-pump and pressure-gage, as they are common means for such purposes in the automobile and railway arts.

Experience has shown that for practical railroad and surface work to be of economical

and profitable use the vehicle with the burner devices must be moved sufficiently rapid to cover a large area in a given time, and this calls for a large amount of fuel in the form of gas. It is desirable, as far as possible, to eliminate friction or obstructions in the passage of the fuel from the source of supply to the burners, and therefore I have provided generator and burner mechanism of large capacity and composed of two sets of relatively large generating-coils or series of rings of pipe 7, horizontally disposed, each positioned at one side and at right angle with the center line of vehicle travel, each coil terminating in a straight portion 8, positioned below and parallel with the coils. The straight portions 8 extend to and are connected with opposite ends of a Bunsen feeder 9, which carries a multiplicity of Bunsen burners 11, vertically disposed. The Bunsen feeder carries numerous individual feed-pipes 10, extending to the rear and to the front thereof, and at the outer end of each individual pipe 10 is a Bunsen burner 11, adapted to burn hydrocarbon fuel. At each end of the Bunsen feeder 9 I provide a suitable quick-closing valve 12, operated by rod 13 for the purpose of regulating the supply of fuel to the burners.

I prefer to use the form of Bunsen burner shown in Fig. 4, in which 14 represents the usual needle-valve and the inner end of rod 14'. I show only two rows of Bunsen burners, one in front and the other at the rear of the Bunsen feeder. It will be apparent my construction will permit a number of rows of burners all to be fed from one Bunsen feeder. It will also be apparent that by increasing the sizes and number of parts great capacity may be obtained. In Fig. 1 the burner devices are in front and in Fig. 2 they are at the rear of the vehicle. The coils 7 and the straight pipe 8 constitute the generator proper, and when the generator is in full operation there will not be any liquid fuel in the Bunsen feeder 9.

The burner mechanism is supported upon an upright frame with parallel side standards 15 and a roller 16, over which the cable 17 runs. The inner end of the cable 18 is adapted to be wound on a drum 19, the shaft of which is supported by suitable bearings on the upper surface of the end of the vehicle, and the outer end of the cable is connected to the forward parts of the frame 20 or at 21 for vertical adjustment of the burner mechanism by means of worm 22, gear 23, shaft

24, and wheel 25. Frame 20 is pivoted to the end of the vehicle, as at 26. Safety-cables 27 are fastened to the standards 15 at 28 to prevent the burner mechanism dropping onto the ground accidentally. 28' denotes a brace-bar to stay the side standards 15.

The tank 29 is for liquid fuel and is connected with supply-pipes 6. Near the tank 10 there is a valve 30 in each pipe to shut off the fuel from the tank when desired.

Supply-pipes 6 are pivotally joined at 31 to allow vertical adjustment of the burner means. 20' is a hood just above and extending the entire length of the Bunsen feeder for the purpose of deflecting the heat downward. The hood is suitably fastened to and supported by the frame 20 near either end behind the inner row of Bunsen burners.

20 Before beginning to operate the burner it is desirable to rotate the needle-valve 14, rod 14', one full turn from closed position. The bunsens are lighted in the well-known manner. When the bunsens are burning the 25 proper mixture of gas and air, the flame may be controlled at will by means of the quick-action valve 12.

Having thus fully described my invention, what I claim as new, and desire to secure by 30 Letters Patent, is—

1. In a vegetation-burner, a Bunsen feeder

carrying a multiplicity of Bunsen burners, in combination with generating devices comprising coiled portions of pipe and straight portions positioned below and parallel with the 35 coils and connected with opposite ends of the Bunsen feeder, and a fuel-regulating valve at each end of the Bunsen feeder.

2. In a vegetation-burner, a Bunsen feeder carrying a multiplicity of Bunsen burners, in 40 combination with a generator composed of a coiled portion and a straight portion positioned below and parallel with the coiled part and connected with the opposite end of the Bunsen feeder, and a fuel-regulating 45 valve between the generator and the Bunsen feeder.

3. In a vegetation-burner, a plurality of horizontally-disposed coils of pipe each coil having a straight extension thereof positioned below and parallel with the coils and constituting a generator, and means for regulating the flow of fuel from the generator, in combination with a Bunsen feeder carrying a multiplicity of Bunsen burners, and means 50 for distributing liquid fuel to the generator.

In testimony whereof I affix my signature in presence of two witnesses.

WILBERT W. LAMB.
